UNITED STATES PATENT OFFICE.

EDWARD BRUNHOFF, OF CINCINNATI, OHIO, ASSIGNOR TO THE BRUNHOFF MANUFACTURING COMPANY, OF CINCINNATI, OHIO, A CORPORATION OF OHIO.

DISPLAY AND VENDING APPARATUS.

Application filed November 2, 1923. Serial No. 672,433.

To all whom it may concern:

Be it known that I, EDWARD BRUNHOFF, a citizen of the United States, residing at Cincinnati, in the county of Hamilton and 5 State of Ohio, have invented certain new and useful Improvements in Display and Vending Apparatus, of which the following is a specification.

My invention relates to improvement in 10 display and vending apparatus. One of its objects is to provide improved means to display for sale a plurality of original packages, as for instance, packages of tobacco or cigarettes. Another object is to 15 provide improved means to display the advertising matter on the original packages and to provide other contrasting advertising matter. Another object is to provide improved means to retain the several original 20 packages in their assembled and relative positions and to prevent unauthorized detachment of any of the original packages or their accidental displacement. Another 25 object is to provide improved means whereby the advertising matter on the front and top of the original packages is housed by means of transparent covering members or equivalent means adapted to display the advertising matter to advantage and to be 30 readily kept clean and to keep the exterior of the original packages bright and clean. Another object is to provide means to hold and display either single or plural rows 35 of original packages and to hold and display original packages having either paper or metal containers. My invention also 40 comprises certain details of form and combination and arrangement of components all of which will be fully set forth in the description of the accompanying drawings, in which:

Fig. 1 is a perspective view of one type of my improved apparatus adapted to hold and display a single row of original containers.

Fig. 2 is a plan view of Fig. 1, provided with a lid member having a panel of transparent material.

Fig. 3 is a perspective view of the lid member of Fig. 2 detached.

Fig. 4 is a perspective view of a sheet metal lid member adapted to be used in place of the lid member shown in Fig. 3.

Fig. 5 is a vertical sectional view taken 55 on line 5—5 of Fig. 1.

Fig. 6 is a sectional detail showing a modification of Fig. 5.

Fig. 7 is a front elevation illustrating a modified type of apparatus adapted to hold two parallel rows of original containers. 60

Fig. 8 is a plan of the apparatus shown in Fig. 7.

Fig. 9 is a perspective view of one of the front advertising and protecting plates of Fig. 7 detached. 65

The accompanying drawings illustrate the preferred embodiments of my invention; as shown in Figs. 1, 2, 3, and 5; a sheet metal frame is provided with a front 15 having channels 16 to detachably support a front advertising plate 17, preferably of plate glass or other transparent material upon the lower portion of which is painted or etched an advertisement of the goods 18, and through the upper portion of 70 which plate the advertising matter 19 upon the front of one or more of the original packages 20 is displayed. 75

A plurality of the original packages 20 arranged in one or more rows and one behind another in the rows are mounted in a shallow inclined receptacle 21, so as to expose the advertising matter 22, on the side edges of the original packages 20. The rear wall 24 of the receptacle 21 preferably 80 extends above the upper edge of the side walls of said receptacle and is provided with hinge eyes 25 by means of which a lid member 26 is hinged to the rear wall 24. The lid 26 is of angular cross section so 85 as to embrace the upper portion of the rear packages 20 and to extend forwardly across the top of all of the original packages 20 to prevent any one of the original packages being detached and removed from the receptacle without first lifting the lid 26. At 90 the front edge of the lid 26 is a latch member 27 adapted to engage over the upper edge of the front plate 19 to retain the lid in its closed position with a limited amount 95 of tension so as to require the receptacle or some part thereof to be held down with one hand while the other hand is employed to lift the lid. I also preferably employ a spring 28 or equivalent means tending to 100 resiliently hold the lid in closed position.

I also preferably attach a bell or equivalent member 30 adapted to be actuated by means of a lever or projection 31 attached to the lid so as to sound an alarm each time 110

the lid is opened to detach one of the original packages, all of which are designed to prevent the original packages becoming too readily detached from the receptacle 5 by accident, or detached by unauthorized persons without attracting the attention of the person in charge of the store. As illustrated in Figs. 1, 2, and 3 only a single row of original packages is employed. Also the 10 top portion of the lid is provided with a transparent section or panel 33 through which seals, trade-marks, or advertising matter 34 located on the upper end of the original packages are exposed to the view 15 of prospective purchasers. As illustrated in Fig. 4 the top of the lid 26 is of sheet metal or other opaque material and is itself employed to carry advertising matter 37. As illustrated in Figs. 1 and 6 the 20 receptacle 21 is provided with sheet metal partitions 38 interposed between the respective original packages in the row or rows. As illustrated in Fig. 5, the partitions 38 are omitted and the original packages 25 are arranged together face to face in a single compartment.

In Figs 7 and 8 I have illustrated an apparatus adapted to contain and display a plurality of rows of original packages, as 30 for instance two rows of the same type and grade of original packages, two rows containing different grades of the same type of original packages, or two rows each containing an independent type of original 35 package. As illustrated in Fig. 7 two separate front plates 40 and 41 are provided and are detachable and interchangeable whereby the display apparatus or either side thereof may be employed at will for different types 40 of original package by changing the front plate 40 and 41 or either one thereof. As illustrated in Figs. 7 and 8 the lid 42 is relatively narrow so as to engage over only a portion of each original package and to 45 thereby as shown in Fig. 8, expose to view the forepart of the advertising matter 44 on the end of the left hand row of original packages and closely adjacent thereto the latter part of the same advertising matter 50 45 upon the end of the right hand row of original packages. The lid 42 is preferably provided with a latch member 46 to engage the upper edge of the front plates 40 and 41, and also with a spring 47 to hold the lid 42 yieldingly in closed position, and is 55 also preferably provided with an alarm sounding element 30 corresponding to the alarm sounding element 30 of Figs. 1 and 2.

The apparatus herein shown and described is capable of considerable modification within the scope of the claims without departing from the spirit of my invention.

What I claim is:

1. A display and vending apparatus com-

prising a supporting frame having a receptacle to receive a plurality of original packages in a row one in rear of another and to present and utilize the advertising matter upon the front of the packages for display purposes, a detachable advertising plate having a transparent section mounted in guides upon the front of said supporting frame, and a lid member extending from rear to front of said supporting frame transversely across the top of said original packages to retain said original packages in position. 65

2. A display and vending apparatus comprising a supporting frame having a receptacle to receive a plurality of original packages in a row one in rear of another and to present and utilize the advertising matter upon the front of the packages for display purposes, a detachable advertising plate having a transparent section mounted in guides upon the front of said supporting frame, and a lid member extending from rear to front of said supporting frame transversely across the top of said original packages to retain said original packages in position, and means carried by said supporting frame to sound an alarm when said lid is lifted to detach one of said original packages. 80

3. A display and vending apparatus comprising a supporting frame having a plurality of receptacles to receive a plurality of original packages one in rear of another in independent rows and to present and utilize the advertising matter upon the front of the original packages, a plurality of advertising plates each having a transparent section through which to disclose the advertising matter upon the front of said original packages detachably mounted in guides upon the front of said supporting member, a lid member extending transversely across the top of said original packages to retain the original packages in position. 95

4. A display and vending apparatus comprising a supporting frame having a receptacle to receive a plurality of original packages in a row one in rear of another and to present and utilize the advertising matter upon the front of the packages for display purposes, a detachable advertising plate having a transparent section mounted in guides upon the front of said supporting frame, and a lid member extending from rear to front of said supporting frame transversely across the top of said original packages to retain said original packages in position, and means to yieldingly retain said lid member in closed position relative to said supporting frame. 100

In testimony whereof, I have hereunto affixed my signature.

EDWARD BRUNHOFF.
